[57] CLAIM

The ornamental design for a replaceable vice jaw lining, as shown and described.

DESCRIPTION

FIG. 1 is a perspective view of the replaceable vice jaw lining.

FIG. 2 is a front elevational view of the invention.

FIG. 3 is a rear elevational view of the invention.

FIG. 4 is a top plan view of the invention.

FIG. 5 is a bottom elevational view of the invention.

FIG. 6 is a left side elevational view of the invention, facing top down.

FIG. 7 is a left side elevational view of the invention, facing bottom down.

FIG. 8 is a perspective view of a second embodiment of the replaceable vice jaw lining.

FIG. 9 is a front elevational view of the invention shown in FIG. 8; and,

FIG. 10 is a rear elevational view of the invention shown in FIGS. 8 and 9.
